(57) **CLAIM**

The ornamental design for an automobile exterior, as shown and described.

DESCRIPTION

FIG. 1 is a front perspective view of an automobile exterior showing our new design; and,
FIG. 2 is a front view thereof.

It will be understood that the broken lines shown in the drawings illustrate portions of the automobile exterior that form no part of claimed design.

1 Claim, 2 Drawing Sheets

FIG. 1

FIG. 2
